UNITED STATES PATENT OFFICE.

FRANK L. McCORMICK, OF NORTH TONAWANDA, NEW YORK, ASSIGNOR TO THE RUDOLPH WURLITZER MANUFACTURING COMPANY, OF NORTH TONAWANDA, NEW YORK, A CORPORATION OF NEW YORK.

TRACKER-BOARD.

1,205,231.

Specification of Letters Patent. Patented Nov. 21, 1916.

Application filed July 23, 1914. Serial No. 852,597.

To all whom it may concern:

Be it known that I, FRANK L. McCORMICK, a citizen of the United States, residing at North Tonawanda, in the county of 5 Niagara and State of New York, have invented new and useful Improvements in Tracker-Boards, of which the following is a specification.

It is customary to extend a comparatively 10 fine screen of woven wire across the ducts of tracker-boards to intercept dust, lint and particles of paper detached from the music sheets passing over the trackers, in order to prevent such substances from interfering 15 with the operation of the valves or other parts of the usual pneumatic actions which are controlled by the tracker boards and music rolls. For this purpose the tracker board is usually divided into separable sec- 20 tions between which the screen is interposed and from which it may be removed from time to time for cleaning it, as required. As heretofore constructed, such screens become clogged in a comparatively short time and 25 require frequent cleaning.

The object of my invention is to so construct the tracker board that it will clog less rapidly and therefore require less frequent cleaning.

30 In the accompanying drawings: Figure 1 is a transverse section of a tracker board embodying the invention. Fig. 2 is an enlarged fragmentary section thereof, on line 2—2, Fig. 1. Fig. 3 is a longitudinal section 35 on line 3—3, Fig. 2, the scale being exaggerated for clearness.

Similar characters of reference indicate corresponding parts in the several views.

1 indicates the rear or base-section of the 40 tracker and 2 the front or face-section, which is removably attached to the rear section by any suitable means. The preferred fastenings are the customary hooks located at opposite ends of the board, one of them 45 being shown at 3, in Fig. 3.

4 indicates the portions of the tracker-ducts or tubes formed in the front section, and 5 the continuation thereof formed in the rear section.

50 Removably arranged between the tracker sections is the dust-screen 6 of fine wire cloth or other suitable material. In the construction shown, this screen is interposed be-

tween two packing sheets or layers 7 of leather or other appropriate material, which 55 may be coextensive with the adjoining surfaces of the tracker-sections. Each of these layers contains openings 8 which register with the respective tracker-ducts, but are considerably larger than the diameter of 60 said ducts, so as practically to form enlargements thereof immediately above and below the screen. Preferably, these openings are rectangular and elongated lengthwise of the tracker, as shown, but they may be of any 65 other suitable form.

In the use of the tracker, the dust, lint, &c., drawn into the mouths of its ducts is first deposited upon the central portion of the screen-area belonging to each duct and 70 then gradually upon the marginal portion of that area opposite the enlargements 8. In ordinary trackers, the screen must be removed and cleaned when the dust, &c., in the course of time covers areas corresponding to 75 the diameter of the ducts. In a tracker embodying this improvement, even when the screen becomes clogged to the extent just mentioned, there still remains a considerable open or unclogged portion for the passage 80 of the air equal to the difference in cross sectional area between the ducts and the enlargements 8, and the tracker board can therefore continue in service for a correspondingly longer period before requiring 85 the screen to be cleaned.

While affording this important advantage, the improvement is exceedingly simple and its cost is but nominal.

My invention is herein shown as applied to 90 a tracker board, but it is also applicable to other duct-boards having one or more air passages provided with a dust screen.

I claim as my invention:

1. A tracker or the like having a duct and 95 a dust-screen extending across the duct, the duct being provided with an enlargement adjacent to both sides of the screen and the walls of said enlargements which face the sides of the screen being both spaced there- 100 from.

2. A tracker divided transversely of its ducts and having a screen removably interposed between its sections, the opposing ends of corresponding duct-sections being pro- 105 vided with enlargements and the walls of

said enlargements which face the sides of the screen being both spaced therefrom.

3. The combination of a tracker divided transversely of its ducts, layers arranged between the sections of the tracker and having registering openings which coincide with the tracker-ducts but are of larger dimensions than the ducts, and a screen interposed between said layers, said layers separating

both sides of the screen from the opposing faces of the tracker-sections.

Witness my hand this 6th day of July, 1914.

FRANK L. McCORMICK.
